United States Patent Office

Des. 228,548
Patented Oct. 9, 1973

228,548

BOTTLE CAP

Maxwell H. Connan, 240 Glen Head Road,
Glen Head, N.Y. 11545

Filed Aug. 18, 1972, Ser. No. 281,703

Term of patent 14 years

Int. Cl. D9—99

U.S. Cl. D9—284

Fig. 1

Fig. 2

Fig. 3

FIG. 1 is a side elevational view of a bottle cap showing my new design;

FIG. 2 is a top plan view thereof; and

FIG. 3 is a bottom plan view thereof.

I claim:

The ornamental design for a bottle cap, substantially as shown.
